(57) **CLAIM**

The ornamental design for a dashboard for electric bicycle, as shown and described.

DESCRIPTION

FIG. 1 is a front perspective view of a dashboard for electric bicycle embodying my new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged view of the selected portion 9 in FIG. 3.

The broken lines shown in the drawings depict portions of the dashboard for electric bicycle that form no part of the claimed design.

The additional broken lines encircling the enlarged views in FIGS. 3, 9 are for annotative purposes only and form no part of the claim thereof.

1 Claim, 9 Drawing Sheets
